UNITED STATES PATENT OFFICE.

ARTHUR NATHAN DOUD, OF CLEVELAND, OHIO, ASSIGNEE TO THE LAKEWOOD ENGINEERING COMPANY, OF CLEVELAND, OHIO, A CORPORATION OF OHIO.

OPERATING MEANS FOR DREDGING-BUCKETS.

1,164,076.

Specification of Letters Patent. Patented Dec. 14, 1915.

Application filed November 18, 1913, Serial No. 801,703. Renewed May 13, 1915. Serial No. 27,933.

To all whom it may concern:

Be it known that I, ARTHUR N. DOUD, a citizen of the United States, residing at Cleveland, in the county of Cuyahoga and State of Ohio, have invented a new and useful Operating Means for Dredging-Buckets, of which the following is a specification.

This invention has reference to improvements in operating means for dredging buckets, and is particularly applicable to the operation of clam-shell buckets.

In accordance with the present invention there is provided an attachment for a derrick boom, or the latter may have the essential features of the attachment built thereinto initially, and the attachment provides a means whereby a single line may be employed for operating the bucket. The usual releasing or trip line, instead of being attached to the bucket, is carried by the boom so that instead of there being a great surplus of line which has to be taken care of as the bucket is raised and lowered, as in prior constructions, the trip line remains practically always of the same length regardless of the position or distance of the bucket from the operator.

Moreover, the present invention has to do with the arrangement whereby the rope or line is roved through the bucket and boom sheaves and with the structures whereby the bucket line is controlled.

The present invention distinguishes in numerous particulars from single line bucket structures as heretofore proposed, which prior bucket structures are customarily operated by means of hook arrangements attached to the bucket proper, and are released by means of trip lines that are attached to a releasing mechanism connected to the bucket.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material

departure from the salient features of the invention.

In the drawings: Figure 1 is an elevation of a boom attachment and bucket embodying the present invention, the bucket being shown close to the boom and closed. Fig. 2 is an end elevation of the structure shown in Fig. 1 with the boom shown in cross section. Fig. 3 is a section on the line 3—3 of Fig. 2, but showing the bucket closer to the boom and open, some of the more distant sheaves being shown in cross section to avoid hiding the rope or line. Fig. 4 is a section on the line 4—4 of Fig. 3 with some parts in elevation and the rope or line and distant parts omitted. Fig. 5 is a side elevation of a boom with the attachment forming a part of the present invention built thereinto.

Referring to the drawings, and more particularly to Figs. 1 to 4, there is shown a portion of the outer end of a boom 1 which may be taken as typical of any suitable derrick boom whether made of wood or metal, and whether of solid construction, as indicated, or of skeleton construction, as is the custom with steel booms. Attached to the boom by bolts 2 or in any other suitable way, is a frame 3 which may be of channel form with a top plate 4 and side or cheek plates 5 all suitably united, the channel member being open at what may be termed the lower or bottom edge. The channel member is attached to the beam near its outer end at the point usually occupied by the sustaining pulley or pulleys for a bucket, the latter being indicated generally at 6, and as in most part the bucket may be of known construction, reference will be made to only such parts of the bucket as it may be necessary to mention in the following description. Mounted in the channel member 3 near the respective ends are sheaves 7, 8, these sheaves being located on opposite sides of the longitudinal center line of the channel member. At an intermediate point the channel member has mounted therein a drum 9 having a journal or spindle 10 projecting through and for a distance beyond one of the side plates 5 and there carrying a friction wheel 11 encircled by a friction band 12, and as this friction band may follow the customary construction, it needs no special

70

detailed description. Extending through the side plate 5 traversed by the extended end of the shaft or journal 10 is a rock shaft 13 carrying at its outer end a rock arm 14 fast thereto, while between the side plates 5 the rock shaft 13 has an eccentric portion 15 in position to engage a plunger 16 mounted in a guide block 17 secured in the channel member between the side plates 5. The rock arm 14 is attached to one end of the friction band 12 by a link 18 having adjustable lock nuts 19 thereon, so that the relation of the band to the arm 14 may be adjusted as needed, while the other end of the friction strap is formed into a loop surrounding a stud 20 mounted on a bearing plate 21 on the corresponding side plate 5, or, if desired, directly upon the plate. Secured to the outer end of the arm 14 is a line 22 which may be and usually is connected to the basic end of the boom and from thence into reach of the operator, the arrangement being such that upon a pull on the line 22 the rock arm is moved in a direction to draw the friction band 12 into engagement with the friction drum 11, so that the band and drum become in effect a brake and the drum 11 being keyed or otherwise made fast to the shaft 10 of the drum 9, the latter is controlled by the brake. Movement of the arm 14 in a direction to apply the brake so moves the cam 15 as to in turn cause a movement of the plunger 16 toward the boom and in the path of the plunger 16 there is a movable hardened steel plate 23 for a purpose to be described. Mounted in the boom 1 adjacent to the sheave 7 is another sheave 24 for a purpose which will hereinafter appear. Mounted on a spindle 25 immediately above the pivot 26 of the two halves of the bucket are three sheaves 27, 28 and 29, respectively, and at a higher point on respective bail arms 30 of the bucket are other sheaves 31 and 32, respectively, and adjacent to the sheaves 31 and 32 and at a somewhat higher point are other idler sheaves 33, 34, respectively, while at appropriate points are guard rollers or sheaves 36. There is provided a single operating rope or cable 37 coming from the winding drum of the derrick engine, not shown, and passed about the sheave 24, thence partly about the sheave 7, thence to the sheave 34 of the bucket, thence about the sheave 27 in underriding relation thereto, thence to and around the sheave 31, returning to and in part encircling the sheave 29, thence to and about the sheave 32, returning to the sheave 28 in underriding relation thereto, and then to the sheave or roller 33, from whence the cable is continued to and in part about the sheave 8, and is then continued to the drum 9 about which the cable is wrapped one or more, and preferably two times, and finally is carried to an eye 38 at the junction point of the

bail arms 30 of the bucket. That run of the rope or cable 37 between the sheave 8 and the drum 9 is located between the plunger 16 and the removable plate 23 so that upon the active movement of the plunger 16 under the impulse imparted by the cam or eccentric 15 the run of the rope between the sheave and drum may clamp against the plate 23. 70

Fig. 5 differs from the structure of the other figures in that there is shown a skeleton steel boom 1^a with sheaves 7^a and 8^a, similar to the sheaves 7 and 8 and mounted directly in the boom 1^a, the latter being provided with side plates 5^a, or being otherwise constructed to support the sheaves. Between the sheaves 7^a and 8^a the boom carries a drum 9^a and outside of one of the side plates 5^a the shaft 10^a of the drum 9^a has keyed thereto a friction or brake drum 11^a encircled by a friction or brake band 12^a, and the latter is coupled to a rock arm 14^a in turn connected to a rope or strand 22^a which it is to be understood leads into convenient reach of an operator. While the plunger 16 is hidden in the structure shown in Fig. 5, it will be understood that it is present and a removable bearing plate 23^a is mounted on the boom 1^a. The structure shown in Fig. 5 is in all essential respects the same as that shown in the other figures of drawing, and the bucket structure is assumed to be present and to be the same as before. Since the sheave 7^a is built into the boom in the structure shown at 5, the sheave 24 is unnecessary, and is, therefore, omitted. 90

In Fig. 1 the bucket is shown as closed and it may be assumed that the bucket is filled and rising. Under these circumstances the brake band 12 is loose and the plunger 16 is out of engagement with that run of the cable 37 extending between the sheave 8 and drum 9. The pull of the cable is in the direction of the roving thereof through the bucket sheaves and the group of sheaves 27, 28 and 29 is held elevated, so that the bucket remains closed and at the same time that run of the cable between the drum 9 and the eye 38 is rising, the bucket following. When the requisite height has been attained, and it is desired to dump the bucket, the strand 22 is actuated to move the rock arm 14 in a direction to tighten the brake band 12 upon the brake drum 11, and at the same time move the plunger 16 against the run of the cable between the sheave 8 and drum 9, so as to force it against the plate 23, thus clamping it in position and augmenting the frictional hold of the drum 9 upon the cable 37, for in large buckets the frictional hold of the cable upon the braked drum 9 may be insufficient. With light outfits the clamping plunger 16 may be omitted, although eminently serviceable when the buckets are large. The bucket is held in the elevated 136

position by the clamped portion of the cable, and the portion of the cable 37 coming from the hoisting engine may be released, whereupon the cable will be slackened where passing about the sheaves carried by the bucket and the bucket will open in the usual manner to dump its contents. The arrangement of the parts is the same for closing the bucket as for opening it, except that the direction of movement of the main portion of the cable 37 is reversed. To elevate or lower the bucket the drum 9 is released from the brake band 12 and the plunger 16 is at the same time retracted.

Since the tripping line or strand 22 is connected to tripping mechanism carried by the boom instead of by the bucket, this line or strand 22 follows all the movements of the boom and is unaffected by any movement of the bucket, wherefore there is but little movement of the operating or trip line, and it is unnecessary that there be any particular surplus thereof, for there is nothing to be taken care of, so far as the trip line is concerned, while the bucket is being raised and lowered. This is brought about by the employment of the structure attached to the boom or built into the boom, as the case may be. Moreover, the manner of roving the operating line through the bucket sheaves and about the friction brake and in operative relation to the clamped plunger, while susceptible of change and modification for different types of buckets, is of importance in connection with the type of bucket illustrated.

In the claims the word rope is used as designating any suitable flexible strand for the purpose having the characteristics of a rope or cable or other similar means.

What is claimed is:—

1. The combination with a derrick boom, of a clam-shell bucket, a single rope and opening and closing means on the bucket responsive to said single rope, direction-changing means on the boom for the rope, and a brake and a clamp on the boom for the rope.

2. In a dredging apparatus, the combination with a clam-shell bucket, of a single rope, bucket opening and closing means on the bucket associated with and responsive to the single rope, and rope-controlling means adapted to be carried by a part of the dredging apparatus other than the bucket and comprising a direction-changing means for the rope, a brake and a clamp for the rope.

3. In a dredging apparatus, the combination with a clam-shell bucket, of a single rope, bucket opening and closing means on the bucket and associated with and responsive to the single rope, and rope controlling means adapted to be carried by a part of the dredging apparatus other than

the bucket and comprising a drum for receiving the rope, a band brake for the drum, a clamp for the rope, and a single operating means common to both the band brake and the clamp.

4. In a dredging machine, the combination with a clam-shell bucket, comprising members hinged together for opening and closing, sustaining members connected to the hinged members at outer portions thereof, and direction-changing members carried by the hinged connections and sustaining members, respectively, of a single rope connected at one end to the sustaining members and roved through direction-changing members on the bucket, and means separate from the bucket for braking and clamping the rope and having direction-changing means associated therewith.

5. In a single rope derrick hoist for clam-shell dumping buckets, a boom, brake means for the single rope mounted on the boom, clamping means for the rope also mounted on the boom adjacent to said brake means, and common operating means for the brake and clamp means.

6. In a single rope derrick hoist for clam-shell dumping buckets, a boom, direction-changing sheaves on the boom spaced apart in the direction of the length of the boom, a brake means for the single rope mounted on the boom between the spaced sheaves, and a clamping means for the rope mounted on the boom between the brake means and one of the sheaves.

7. In a single rope derrick hoist for clam-shell dumping buckets, a boom, direction-changing sheaves on the boom spaced apart in the direction of the length of the boom, a brake means for the single rope mounted on the boom between the spaced sleeves, and a clamping means for the rope mounted on the boom between the brake means and one of the sheaves, the brake means and the clamping means being provided with a single operating means common to both.

8. In single-rope derrick hoists for dumping buckets, the combination with the derrick boom of a drum mounted on the outer end portion of the derrick boom in position to be encircled by the single hoisting rope, a brake means for the drum, a clamping means adjacent to the drum and in position to engage the hoisting rope, and a common operating means for the brake means and clamping means also carried by the boom and capable to move the brake means and clamping means simultaneously in the same direction.

9. In single-rope derrick hoists for dumping buckets, a boom, a drum mounted on the boom in position to be encircled by the single hoisting rope, a brake means for the drum, direction changing means for the hoisting rope adjacent to the drum and also mounted

on the boom; a clamp means between the drum and direction changing means in position to engage the hoisting rope, and operating means for the brake means and clamp means common to both and operable to move both simultaneously to the active or inactive position.

10. In single-rope derrick hoists for dumping buckets, a boom, a drum mounted on the boom in position to be encircled by the single hoisting rope, a direction changing sheave mounted on the boom adjacent to the drum, a brake for the drum, a clamping means on the boom between the sheave and drum and comprising a plunger movable to engage the run of the rope between the sheave and drum, and a common operating means for the brake and plunger carried by the boom.

11. In single rope derrick hoists for dumping buckets, a boom, a drum mounted on the boom in position to be encircled by the single hoisting rope, a direction-changing sheave mounted on the boom adjacent to the drum, a brake for the drum, a clamping means on the boom between the sheave and drum and comprising a plunger movable to engage the run of the rope between the sheave and drum, and a common operating means for the brake and plunger carried by the boom, said clamping means including a removable plate in coactive relation to the plunger to receive the thrust of the plunger with the rope interposed.

12. In single rope derrick hoists for dumping buckets, a boom, a drum mounted on the boom in position to be encircled by the single hoisting rope, direction changing sheaves on opposite sides of the drum, and braking means for the drum.

13. In single rope derrick hoists for dumping buckets, a boom, a drum mounted on the boom in position to be encircled by the single hoisting rope, direction changing sheaves on opposite sides of the drum, a brake means for the drum, a clamping means intermediate of the drum and one of the sheaves, and common operating means for the braking means and clamping means.

14. In single rope derrick hoists, the combination with a clam-shell dumping bucket having sheaves adjacent to the bucket members and other sheaves more distant therefrom, of a derrick boom, a drum on the der-

rick boom at the outer portion thereof, a 55
brake means on the boom for the drum, direction changing means on the boom adjacent to the drum, and a single hoisting rope connected at one end to the bucket and then wrapped about the drum and from thence roved through the several sheaves on the 60 bucket and boom.

15. In single rope derrick hoists, the combination with a dumping bucket having sheaves adjacent to the bucket members and other sheaves more distant therefrom, of a 65
derrick boom, a drum on the derrick boom at the outer portion thereof, a brake means on the boom for the drum, direction changing means on the boom adjacent to the drum, and a single hoisting rope connected at one 70
end to the bucket and then wrapped about the drum and from thence roved through the several sheaves on the bucket and boom, the boom also carrying a clamping means adjacent to the drum with direction changing means adjacent to the clamping means, and common operating means on the boom for the braking means and clamping means.

16. The combination with a clam-shell bucket, of a single sustaining rope connected 80
thereto, opening and closing means for the bucket located thereon and means in coöperative relation to and associated with the single rope and bucket, whereby the lifting and lowering and the opening and closing 85
of the bucket at any point in its up and down movements are brought about by the single rope.

17. The combination with a derrick boom and a clam-shell bucket, of a single sustaining 90
rope for the bucket, and means on the bucket in coöperative relation to and associated with the single rope and on the boom in coöperative relation to and associated with the single rope, whereby the lifting and 95
lowering of the bucket and the opening and closing of the bucket at any point in its up and down movements are brought about by the single rope.

In testimony, that I claim the foregoing as 100
my own, I have hereto affixed my signature
in the presence of two witnesses.
